United States Patent

Des. 236,605

Patented Sept. 2, 1975

236,605

MARINE VEHICLE

James Nelson Johnson, 120 S. Birdneck Road,
Virginia Beach, Va. 23453

Filed Mar. 22, 1974, Ser. No. 453,934

Term of patent 14 years

Int. Cl. D12—06

U.S. Cl. D12—69

FIG. 1

FIG. 3

FIG. 2

FIG. 4

FIG. 5

FIG. 6

FIG. 7

FIG. 1 is a left side elevational view of a marine vehicle embodying my new design, the right side being a mirror image thereto;

FIG. 2 is a top plan view thereof;

FIG. 3 is a front elevational view thereof;

FIG. 4 is a rear elevational view thereof;

FIG. 5 is a view, partially in section, of forward components thereof, taken on the line 5—5 of FIG. 1;

FIG. 6 is an elevational view of certain of the components of FIG. 5, taken on the line 6—6 of FIG. 5; and

FIG. 7 is a sectional view of one of the components of FIG. 5, taken on the line 7—7 of FIG. 5.

I claim:

The ornamental design for a marine vehicle, as shown and described.
